GARMENT PRESS

Otto W. Schaum, Philadelphia, Pa.

Application November 5, 1935, Serial No. 48,287

9 Claims. (Cl. 38—36)

This invention relates to an improvement in a garment press.

In the operation of garment presses it is often desirable to adjust the head upon the garment supporting means to compensate for differences in thickness of the work or for other reasons. By my invention I provide simple means for readily adjusting the head relatively to the garment supporting means. Other objects of the invention 10 will appear from the following description and the claims appended thereto.

In carrying out my invention I provide a simplified main head operating means and additional means interconnecting the head carrying member and the frame for adjusting the head relatively to the garment supporting means.

The invention will best be understood if the following description is read in connection with the accompanying drawings in which

20 Fig. 1 is a side elevation of the device showing the head in open position.

Fig. 2 is a side elevation of the head and head supporting and adjusting means partly in section taken on the line 2—2 of Figure 3, and

25 Fig. 3 is a top plan view taken on the line 3—3 of Figure 2.

The press shown in the drawings comprises a frame 10 having near its front an upwardly extending portion 11 on which is mounted the stationary garment support or buck 12 which may be of any suitable structure and customarily is a hollow padded member heated by steam circulated through an inner chamber. The rear portion of the frame has an upwardly extending portion 13 upon which is pivotally mounted the head-supporting member 14 in a manner to be hereinafter described. The head 15, supported by the member 14, may be of any suitable kind to cooperate with the garment support 12, and may also 30 be hollow and heated by steam. No steam circulating system is illustrated or described herein since it forms no part of the present invention, but, as will be understood by those skilled in the art, any suitable circulating system may be used.

45 Also supported by the frame 10 is an integral triangular lever 16 which is pivoted upon the pivot 17 near the base of the frame. At one free apex of the triangular lever 16 is the treadle 18 while the other free apex is pivotally connected at 19 to the link 20, which is pivotally joined to the head-supporting member 14 at 21. Intermediate the head-supporting member 14 and frame, and as illustrated, extending between 50 the pivots 17 and 21 is a telescopic rod 22 main-

tained under tension by the spring 23 contained within the housing 24.

When the treadle 18 is depressed the triangular lever 16 will move forward thus straightening the link 20 and raising the rear portion of the pivoted head supporting member 14 thereby closing the head 15 upon the garment support 12.

The operation of closing the head 15 upon the garment support 12 may be performed either by operation of the treadle 18 or by use of the customary handle 40 on the head 15.

When it is desired to increase the pressure of the head 15 upon the garment support 12, beyond the degree which can readily be obtained by means of the treadle 18, or when for any reason an adjustment of the head relative to the garment support is desired, this may be accomplished according to my invention by means of the lever 25. This lever at its rear end is rotatably joined to the frame by the pivot 26. Intermediate its ends the lever 25 is joined at 27 to the head-supporting member 14, and at its front end it is threadedly engaged by a fixed screw 28 carried on the head-supporting member 14 by the bracket 29. As illustrated the screw or element 28 is provided with a handwheel 30 for convenience in operating. By turning the handwheel 30 the front end of the lever 25 will be raised or lowered on the screw 28 thus rotating the member or lever 25 and thereby rotating the head-supporting member and consequently adjusting the position of the head 15 with respect to the garment support 12.

When the press is in closed position the vertical arm of the triangular lever 16 and the link 20 will assume a straight line position so that even if the operator's foot is removed from the treadle 18 the head will remain in closed position. Movement of the treadle in the opposite direction of course enables the head 15 to be lifted.

As illustrated herein the rear end of the head-supporting member 14 is enlarged thus constituting a counterweight which aids the spring 23 in returning the press to open position. The head 15 also has a handle 40 to enable the operator to press it down by hand also if he wishes.

What I claim is:

1. A garment press comprising a frame, a garment support, a head, and a head-supporting means, operating mechanism connected to said head-supporting means and a lever pivotally mounted intermediate its ends on said head-supporting means and having one end pivotally connected to said frame and the other end adjustably connected to the head-supporting means.

2. A garment press comprising a frame, a garment support, a head, a head-supporting member, operating means connected to said member, a lever pivotally mounted on said member and an adjusting means for the lever on said member to vary the relative positions of the two, the lever being connected to said frame and being engaged by said adjusting means.

3. A garment press comprising a frame, a garment support, a head, a head-carrying member, operating means for said member, and a lever rotatably joined to said frame and having an adjustable connection with said head-carrying member to vary the positions of said lever and head and a connection to said head-carrying member intermediate its connection to said frame and said adjustable connection.

4. A garment press comprising a frame, a garment support, a head, a head-carrying member, operating means for opening and closing said head-carrying member, and auxiliary means for adjusting the position of the head relative to said garment support comprising an adjusting screw on said head-carrying member and a lever interconnecting the frame and said adjusting screw, and having an intermediate pivotal connection to said head-carrying member.

5. A garment press comprising a frame, a garment support, a head, and head-supporting and operating means, said head-supporting means comprising two members one of which interconnects the head and the said operating means and has an adjusting element thereon and the other of which interconnects the frame and said adjusting element, said second mentioned member being movably joined to the first mentioned member intermediate its said connections to the frame and adjusting means.

6. A garment press comprising a frame, a garment support, a head and head-supporting and head-operating means, said head-supporting means comprising two pivoted members, an adjusting element carried by one of said members, the other member having pivotal connection with the frame and being engaged by said element, the first member being movably secured to the other member at a point between said connection and said element.

7. A garment press comprising a frame, a garment support, a head, head supporting means, and head operating means, the head supporting means comprising two parts one of which interconnects the head and the operating means and is pivoted on the second part, said second part being pivoted on the frame and having an adjustable connection with said first part.

8. A garment press comprising a frame, a garment support, a pressing head, means for supporting the pressing head, and operating means therefor, said pressing head supporting means comprising two members movably connected together intermediate their ends, one of said members interconnecting the head and said operating means and the other of said members being pivotally supported on said frame and having a second adjustable connection with said first member.

9. A garment press comprising a frame, a garment support, a head, a head-supporting member, operating means for said member, and head-adjusting means comprising an element on said member, and mounting means for interconnecting the frame and said head supporting member, said mounting means being engaged by said element to vary the position thereof with respect to said member.

OTTO W. SCHAUM.
